CLOTHES HAMPER

Joseph Rubin, Philadelphia, Pa.

Application July 26, 1938, Serial No. 221,371

7 Claims. (Cl. 217—17)

The present invention relates to a certain new and useful construction in clothes hampers. It relates more particularly to hampers of the rigid-frame type as distinguished from the flexible woven-basket type.

It is the object of the present invention to form a clothes hamper which, while having a rigid frame, will have the advantages of the flexible woven-basket type insofar as it will be 10 ventilated throughout its sides, and one which can be inexpensively manufactured and one which will nevertheless be durable and serviceable.

With the above and other objects in view, 15 which will appear more fully from the following detailed description, the present invention consists of a clothes hamper including a rigid base, a rigid upper frame in alignment with said base, and having the same external contour as the 20 base, and grooved rigid upright corner members intermediate the base and upper frame and rigidly connected with each at the corners thereof, and a series of inclined and overlapping slats extending horizontally between adjacent upright 25 corner members and extending into and held by the grooves thereof generally to fill the space between the base and the upper frame to form ventilated sides for the hamper, and a hinged or other suitable lid associated with said upper frame.

The present invention consists of other novel features and details of construction, all of which will appear more fully from the following detailed description.

For the purpose of illustrating the invention, there is shown in the accompanying drawing one form thereof which is at present preferred, since the same has been found in practice to give satisfactory and reliable results, although it is 40 to be understood that the various instrumentalities of which the invention consists can be variously arranged and organized and that the invention is not limited to the precise arrangement and organization of the instrumentalities 45 as herein shown and described.

Referring to the drawing in which like reference characters indicate like parts,

Figure 1 represents a perspective view of a clothes hamper embodying the present invention.

Figure 2 represents a section of line 2—2 of Figure 1 on a somewhat enlarged scale, showing the relationship between the base and one of the corner posts and the inclined slats (the relationship is the same at each of the four corners).

Figure 3 represents a section on line 3—3 of Figure 1.

In the embodiment of the invention illustrated in the drawing, the base designated generally by the numeral 5 is preferably formed of 5 a rectangular frame designated generally by the numeral 6, upon which rests, and to which is fastened, a base board 7 preferably perforated at suitable intervals as at 8. The base frame 6 is formed of the front frame member 9, the rear 10 frame member 10 and the left side frame member 11 and the right side frame member 12. These frame members may be fastened to each other along mitered lines or may be tongued or grooved or rabbeted at their juncture zones or 15 may otherwise be fastened to each other by suitable metallic fastenings.

At the four corners of the lower frame 5, suitable short legs 13 are preferably provided to raise the base off the floor 14 a slight distance. 20

An upper frame designated generally by numeral 15 is similarly formed of front frame member 16, rear frame member 17 and left frame member 18 and right frame member 19, which may be similarly joined by any suitable means as here- 25 inabove indicated.

Intermediate the base frame 6 and the upper frame 15, upright corner members or posts 20, 21, 22 and 23 are provided, at the respective four corners of said frames and affixed thereto 30 by suitable fastening means, such as those indicated at 24 by any other suitable means. The corner posts 20, 21, 22 and 23 are preferably quarter-round pieces of wood as indicated more particularly in Figure 2, with grooves 25 ex- 35 tending along the two flat faces 26 thereof, preferably the full length of the posts. Within the grooves 25, thin wooden slats 27 are placed in the manner indicated in Figures 1, 2 and 3, with each successive slat slightly overlapping the 40 upper edge of the flat beneath it. The width of the groove 15 and the thickness of the slats are so related to each other that the slats will overlap each other only to a limited extent. The slats are inserted in the grooves before the 45 upper frame 15 is applied to the upper ends of the posts.

To the rear upper frame member 16 a lid 28 is hingedly secured by means of the hinges 29 to form an upper closure, as indicated par- 50 ticularly in Figure 3. Suitable rubber bumpers 30 may also be provided on the front frame member 16 to support the lid 28 level when in the closed position indicated in Figure 3.

While the slats 27 overlap each other slightly, 55

yet owing to the fact that the slats are relatively thin wooden strips, the contact between the slats is not solid but is indeed such as to afford ventilation throughout the sides of the 5 hamper, in somewhat the same fashion as a woven basket affords ventilation.

By the construction of the present invention, the hamper while possessing a rigid frame is provided with sides which are inherently flexible 10 and resilient.

The present invention may be embodied in other specific forms without departing from the spirit or essential attributes thereof, and it is therefore desired that the present embodiment 15 be considered in all respects as illustrative and not restrictive, reference being had to the appended claims rather than to the foregoing description to indicate the scope of the invention.

Having thus described the invention, what is 20 hereby claimed as new and desired to be secured by Letters Patent, is:

1. A clothes hamper comprising a polygonal shaped and generally rigid base, a similarly shaped rigid upper frame, rigid upright corner 25 posts intermediate the base and upper frame at each of the corners thereof, and affixed thereto, a pair of juxtaposed upright grooves in each of said corner members, with each groove in each corner member facing and being in operative alignment with a groove in each of the adjacent corner members, a series of thin flexible horizontal slats generally filling each of the spaces between the base and upper frame and adjacent corner members, with their ends 30 projecting into said grooves and retained thereby and with each slat slightly overlapping the adjacent slat, the width of said groove and the thickness of said slats being so related to each other that the overlapping of the slats will be limited by the width of the groove.

2. A clothes hamper comprising a polygonal shaped and generally rigid base formed of an outlining frame and a baseboard generally filling the space within the frame, a similarly shaped rigid upper frame, rigid upright corner posts 45 intermediate the base and upper frame at each of the corners thereof, and affixed thereto, a pair of juxtaposed upright grooves in each of said corner members, with each groove in each corner member facing and being in operative alignment with a groove in each of the adjacent corner members, a series of thin flexible horizontal slats generally filling each of the spaces between the base and upper frame and adjacent corner members, with their ends 50 projecting into said grooves and retained thereby and with each slat slightly overlapping the adjacent slat, the width of said groove and the thickness of said slats being so related to each other that the overlapping of the slats will be limited by the width of the groove.

3. A clothes hamper comprising a polygonal

shaped and generally rigid base formed of an outlining frame and a perforated baseboard generally filling the space within the frame, short legs in the corner of said base, a similarly shaped rigid upper frame, rigid upright corner posts intermediate the base and upper frame at each of the corners thereof, and affixed thereto, a pair of juxtaposed upright grooves in each of said corner members, with each groove in each corner member facing and being in operative alignment 10 with a groove in each of the adjacent corner members, a series of thin flexible horizontal slats generally filling each of the spaces between the base and upper frame and adjacent corner members, with their ends projecting into said grooves 15 and retained thereby and with each slat slightly overlapping the adjacent slat, the width of said groove and the thickness of said slats being so related to each other that the overlapping of the slats will be limited by the width of the groove. 20

4. A cabinet comprising a polygonal shaped and generally rigid base, a similarly shaped rigid upper frame, rigid upright corner posts intermediate the base and upper frame at corners thereof, and affixed thereto, an upright groove in each of said 25 corner posts, each groove facing and being in operative alignment with a corresponding groove in the adjacent corner post, and a series of horizontal slats generally filling the space between the base and upper frame and adjacent corner 30 posts, with their ends projecting into said grooves and with each slat partially overlapping the adjacent slat, and with each slat vertically supporting the slat above it.

5. A cabinet including at least one rectangular 35 side having opposed frame members, said frame members each having a groove facing a similar groove in the opposed frame member, and a series of partially overlapped slats having their ends projecting into said grooves, the width of said 40 groove and the thickness of said slats being so related to each other that the overlapping of the slats will be limited by the width of the groove.

6. A cabinet including at least one rectangular side having opposed frame members, said frame 45 members each having a groove facing a similar groove in the opposed frame member, and a series of slats extending between said members and having their ends projecting into said grooves, and with each slat partially overlapping and supporting the adjacent slat. 50

7. A cabinet including at least one rectangular side having generally vertical opposed posts, said posts each having a groove facing a similar groove in the opposed post, and a series of generally horizontal slats having their ends projecting into said grooves, and with each slat partially overlapping and contacting the adjacent slat, and with each slat vertically supporting the slat above it. 55
